CLOSURE FOR HANDBAGS

Gus Green, New York, N. Y.

Application November 18, 1943, Serial No. 510,822

3 Claims. (Cl. 292—17)

This invention relates to closures for handbags, pocketbooks, and other receptacles, and has for its principal object the provision of a device which may be composed in whole or in part of plastic, and which will provide a simple, effective and sturdy closure.

The invention contemplates the provision of a so-called "snap lock" applied to the bag frames, the elements or parts of said lock being integrally formed with parts of the frames, whereby simplicity in construction as well as ease and economy in manufacture is assured.

The invention further contemplates the provision of a bag frame composed of a pair of hingedly-connected frame members provided with elements in the form of face plates arising from said frame members, said face plates being formed with turned-back tongues constituting locking loops, which in the closed position of the bag are sprung past one another with a snap action to retain the frame members together, or the bag in closed condition.

In the accompanying drawing, wherein an illustrative embodiment of the invention is shown:

Fig. 1 is a front elevation of a bag frame, provided with the improved closure means;

Fig. 2 is a plan view of the same;

Fig. 3 is a face view of one of the frame members, with a part of the same broken away to disclose the face plate;

Fig. 4 is a face view of one of the face plates; and

Fig. 5 is a plan view of the same.

The improved closure means is preferably adapted for use in connection with handbags, pocketbooks, and similar receptacles of the character in which the body of the bag is attached to a pair of hingedly-connected frame members, said members being shown at 1 and 2 and connected by the hinges 3 of conventional form.

Secured to the inner face of each of the frame members 1 and 2 at the top thereof is a face plate. That shown at 4 is secured to the face of the frame member 1 by the screws 5 or similar fastening means, while that shown at 6 is similarly secured to the inside face of the frame member 2.

The face plates 4 and 6 are preferably composed of plastic or some similar material. The frame members 1 and 2 may also be of plastic, or of wood, metal, or any other material suitable for the purpose. Also, while the face plates 4 and 6 are herein disclosed as being attached to the frame members 1 and 2 by screws or other fas-

tening elements, it will be obvious that said plates may, if desired, be formed integrally with the frames.

When the bag is closed, or when the two frame members are brought together as in Figs. 1 and 2, the two face plates are in contact. Each face plate is provided with an integrally-formed top part 7 extending above the top of the frame member on which the face plate is secured, said top part 7 being provided with the locking means to be described. Said locking means consist of two looped elements 8 and 9, one of each of which is formed on the top parts 7 of the face plates 4 and 6, respectively. The manner in which each of the loops 8 and 9 is formed will be apparent from Fig. 4, wherein it will be seen that the face plate 6 therein shown is initially a flat strip of plastic or similar sheet material, longitudinally slitted as at 10 to provide a tongue 11. Said tongue 11 is folded or turned back into a rounded loop 9. The loop 8, integrally formed on the other face plate 4, is similarly produced, the loops so formed being oppositely disposed and provided with the ornamental free ends or tabs 12.

15 The position of the two loops relative to one another is such that when the bag is closed to bring the two frame members 1 and 2 together, the loops will be sprung past one another with a snap action, and will remain in such overlying relation to constitute a snap closure to hold the bag closed. To open the bag merely requires the imposition of sufficient pressure on the loops to spring one past the other.

20 25 The improved closure means is preferably adapted for use in connection with handbags, pocketbooks, and similar receptacles of the character in which the body of the bag is attached to a pair of hingedly-connected frame members, said members being shown at 1 and 2 and connected by the hinges 3 of conventional form.

30 35 While the locking loops are herein shown as being of a certain design, it will be apparent that the design thereof, as well as other features, may be materially modified without departing from the spirit of the invention.

40 45 50 What I claim is:

1. A closure means for handbags and the like having a frame member including a flat face plate extending for the length of the frame, said plate having an integral upward continuation provided with a free-end part doubled back upon itself in

an open loop to form a locking member, said loop having an out-turned tab portion.

2. A closure means as provided for in claim 1, in which the upward continuation of the face plate is in the same plane as the body of the face plate.

3. A closure means for handbags and the like, comprising a bag frame composed of two pivotally connected sections, each of said sections having a flat face plate of a plastic material, said plates constituting the inner faces of the frame sections

and extending for the full length of the frame and being in abutment when the bag is closed, each of said plates having an integral upwardly extending part in the same plane as the face plate, said part having a free-end portion doubled back upon itself in a complete open loop, each loop having an out-turned tab portion, the loops in the two plates being sprung past one another with a snap action when the frame sections are in closed position.
